LOAD BINDER

Ellsworth Moore Smith, Baltimore, Md., assignor
to The Canton Cast Products Company, Can-
ton, Ohio, a corporation of Ohio

Application January 16, 1947, Serial No. 722,443

6 Claims. (Cl. 254—78)

1

This invention relates generally to tensioning devices and particularly to load binders or tension-pull loaders for use with a chain or similar means to bind a load of logs and the like.

An object of the invention is to provide an improved load binder by which a chain can be tightened on throw of the binder's lever arm in either direction.

Another object of the invention is to provide an improved load binder in which certain of a plurality of relatively movable chain engaging hooks can be held against relative movement for locking the binder in load binding position.

Other objects and advantages of the invention will appear hereinafter in the detailed description, be particularly pointed out in the appended claims and illustrated in the accompanying drawings in which:

Figure 1 is a perspective view of a load binder embodying the present invention, the load binder being shown in open position and applied to the opposite ends of a load encircling chain.

Figure 2 is a side elevational view of the binder of Figure 1 in closed position with portions broken away, and

Figure 3 is a side elevational view of the lever of the binder with the hook attachments removed and part of the handle broken away, the lever being shown on an enlarged scale.

Referring now in detail to the drawings illustrating a preferred embodiment of the invention and in which like reference characters designate like parts, the improved load binder has a lever 10. Adjacent one end, the lever is offset and bifurcated to provide a pair of spaced arms 11, the outer ends of which are formed as a pair of aligned hooks 12. While the arms 11 may be spaced throughout their length, the upper edge of the lever preferably extends between and connects the arms almost to their hooked ends, thus forming a downwardly opening U-shaped bifurcation, slot or channel 13 defined in part by the arms.

On the offset portion of the lever, inwardly of its hooked end, are provided a pair of outwardly facing trunnions 14 through which the ends of a clevis or yoke 15 are pivotally connected to the lever. Intermediate the trunnions or pivot of the clevis and the hooked end 12 of the lever, with its inner end received or seated within the

2

slot 13, is an arm or linkage 16 which is pivotally attached to the lever through a pin 17 or like means.

Adjacent their outer or free ends the clevis 15 and the arm 16 are provided with hooks 18 and 19, respectively. These hooks are preferably swivelly secured to their associated members, as by the swivelly mounted eyelets 20, and may be connected to the eyelets either directly or through links 21, depending upon the spread desired.

As shown in Figure 1, the clevis 15 and the arm 16 are preferably pierced adjacent their outer ends to provide openings or holes 22 and 23, respectively.

From Figure 2 it will be seen that these openings are positioned to align with corresponding openings in the lever when the load binder is completely closed. Of the latter openings, one may conveniently be that defined by the concave inner faces of the hooks 12 and the other an opening 24 piercing the arms 11 adjacent their inner ends. With this construction it is possible to lock either or both of the pivoted members 15 and 16 against pivotal movement relative to the lever by inserting a locking pin

25 through one or both of the sets of aligned openings one set being the opening 22 in the clevis and the inner faces of the hooks 12, and the other openings 23 in the arm and 24 in the lever. Such a locking pin may conveniently be

20 formed of a cotter pin attached to the lever by a connecting chain 26 of convenient scope.

In binding together a load of logs and the like it is customary to encircle the logs with a chain 27. After the logs have been so encircled the 35 load binder is applied. In applying the binder, the hook 19 secured to the arm 16 is first engaged in a link in one of the free ends of the chain. As will be apparent, this hook remains in engagement with the chain and serves as the anchor for the binder throughout the subsequent operations or movements of the latter. With the binder in the open position of Figure 1, the chain is then stretched manually to the extent practicable and the hook 18 engaged in the nearest link in the other end of the chain. The lever 10 is then thrown or moved to the closed position illustrated in Figure 2, the inner ends of the clevis and arm, in process, reversing position. By this operation the slack in the chain 27 is 40 reduced by substantially twice the spacing be-

tween the pivoted ends of the clevis and arm. At this stage the nearest link in the loose portion of the end of the chain engaged by the hook 18 secured to the clevis 15 is inserted sideways in the hooks 12 of the arms 11 and the next higher link in the chain slid edgewise in the space between the hooks. With one end of the chain 27 thus gripped by the hooks 12 and the other end still engaged by the hook 19 secured to the arm 16, the lever 10 is thrown or moved in the opposite direction until it again assumes the open position shown in Figure 1. In process the slack in the chain 27 is further reduced by substantially twice the distance between the pivot pin 17 and the hooks 12. At the same time tension is shifted from the hook 18 on the clevis to the hooks 12 forming the hooked end of the lever, enabling the former to be disengaged from the chain. After the lever has again reached open position a second bite is taken on the chain by reengaging the hook 18 with the nearest link in the adjacent end of the chain and the lever is then thrown for a second time to closed position, releasing in process the hooks 12 and enabling them to take another bite on the chain after the lever has reached closed position. Thereafter these steps are repeated as often as necessary to eliminate slack from the chain 26 and bind the load tightly together.

The last throw of the lever in tightening the chain is preferably to closed position. At that point, the opposite ends of the chain are engaged by the hooks 18 and 19 and the clevis and arm are folded along the lever with the sets of locking pin receiving openings in the clevis 15, arm 16 and lever 10 in alignment. A locking pin 25 is then inserted in one or both of the sets of openings to interlock the lever and one or both of the pivoted members against pivotal movement and thus lock the load binder in binding position.

To release the load the locking pin is removed and the lever arm thrown toward open position. As the lever approaches open position a link in the loose portion of the end of the chain engaged by the hook 18 is gripped by the hooks 12. The throw of the lever to open position is then completed relieving the hook 18 from tension and enabling it to be released. The lever is next thrown toward closed position with one end of the chain engaged by the hooks 12, further slackening the chain. Before reaching closed position the hook 18 is reengaged and the throw then completed, thereby transferring the load from the hooks 12 to the hook 18 and enabling the former to be released. These operations are repeated in sequence until the tension on the chain has been released sufficiently to enable the load binder to be disengaged and the chain removed from the load.

From the foregoing detailed description of the invention it will be apparent that there has been provided an improved load binder of relatively simple and rugged construction which is capable of increasing the tension applied to a chain on throw of its lever arm in either direction. Since one of the hooks, that carried by the arm 16, remains in engagement with the chain to which it is applied throughout both tensioning and releasing operations, the improved load binder is adaptable as well to the tightening of fences and like operations as to the tightening of a load binding chain. It should be understood that the described and disclosed embodiment is merely exemplary of the invention and that all modifica-

tions are intended to be included which depart neither from the spirit of the invention nor the scope of the appended claims.

Having described my invention, I claim:

1. A load binder comprising a lever having a slotted end portion terminating in a bifurcated hooked end, a clevis pivotally embracing said end portion inwardly of said hooked end, hook means secured to the outer end of said clevis, an arm pivotally attached to said lever within said slotted end portion and intermediate the pivot of said clevis and said hooked end, and hook means secured to the outer end of said arm, said last-named hook means being grippable with one end of a chain, and said hooked end and first-named hook means being sequentially grippable with the opposite end of said chain for tightening said chain on throw of said lever in either direction.

2. A tensioning device comprising a lever having a bifurcated hooked end, a clevis pivotally attached to said lever inwardly of said hooked end, hook means, means swivelly securing said hook means to the outer end of said clevis, an arm pivotally attached to said lever intermediate the pivot of said clevis and said hooked end, second hook means, and means swivelly securing said second hook means to the outer end of said arm.

3. A load binder comprising a lever having a hooked end, a clevis member pivotally attached to said lever inwardly of said hooked end, a hook secured to the outer end of said clevis, an arm member pivotally attached to said lever intermediate the pivot of said clevis and said hooked end, a hook secured to the outer end of said arm member, and means carried by said lever and engageable with one of said members and said lever for locking said lever and member against relative movement.

4. A load binder comprising a lever having a bifurcated hooked end, a clevis member pivotally embracing said lever adjacent its hooked end, a hook, means swivelly securing said hook to the outer end of said clevis member, an arm member pivotally attached to said lever within said bifurcation intermediate the pivot of said clevis and said hooked end, a second hook, means swivelly securing said second hook to the outer end of said arm member, and means carried by said lever and engageable with either of said members for locking said lever and member against relative movement.

5. A load binder comprising a lever having an end portion offset therebelow and terminating in a bifurcated hooked end, said end portion having a downwardly opening slot, a clevis member pivotally embracing said end portion intermediate longitudinal ends of said slot and inwardly of said hooked end, an arm member pivotally attached to said lever within said slot intermediate the pivot of said clevis member and said hooked end, a hook associated with each of said members, means for swivelly securing each of said hooks to a free end of the associated of said members, said hooks being engageable with links adjacent opposite ends of a load-encircling chain, said lever when thrown in one direction tightening said chain, enabling a loose portion of the end of said chain engaged by said clevis-secured hook to be gripped by said hooked end and, when thrown in the opposite direction, with the chain then engaged by said arm-secured hook and said hooked end, further tightening said chain.

6. A load binder comprising a lever having a bifurcated hooked end, a hook, means for pivotally and swivelly attaching said hook to said lever in-

wardly of said hooked end, a second hook, means for pivotally and swivelly attaching said second hook to said lever intermediate the pivot of said first hook and said hooked end, said second hook being grippable with one end of a load-encircling chain and said hooked end and said first hook being sequentially grippable with the opposite end of said chain for tightening said chain on throw of said lever in either direction.
